GEORGE WILLIAM ALSTON BROWN, OF LONDON, ENGLAND, ASSIGNEE OF TWO THIRDS
TO GEORGE PILKINGTON MILLS AND CLEMENT TALBOT LIMITED, OF LONDON,
ENGLAND.

CARBURETER.

1,103,364.

Specification of Letters Patent. Patented July 14, 1914.

Application filed February 18, 1913. Serial No. 747,432.

To all whom it may concern:

Be it known that I, George William Alston Brown, a subject of the King of England, residing at North Kensington, London, England, have invented certain new and useful Improvements in Carbureters for Internal-Combustion Engines, of which the following is a specification.

This invention relates to improvements 10 in carbureters and has particular reference to that type of carbureter in which the air valve is provided with a mixing or combining chamber or passage in communication both with the fuel and the air supply. 15 Preferably such a valve is held on its seat by gravity and is adapted to be lifted by the suction produced in the engine-cylinder. This type of valve may comprise a conical head seated on an aperture leading from 20 the air supply to the throttle valve. It is made of suitable weight or is weighted so that, in the preferred construction, it may return by gravity to its seat. It carries in it a fuel feed in the form of an aspirator 25 tube disposed in a supplemental air passage or combining chamber on the throttle side of the valve and to this combining chamber air is supplied by passages extending through the body of the valve and opening 30 on the underside thereof into the air passage.

The present invention relates to certain novel improvements which enable a carbureter of the general type referred to above to produce a more thorough mixture of fuel 35 and air than heretofore.

According to this invention there is combined with a carbureter of the type hereinbefore referred to an atomizer arranged immediately above the fuel outlet from the 40 carbureter and between it and the throttle. Preferably the atomizer is a disk arranged close to but clear of the fuel outlet and is adjustable in its relation thereto. The disk may have, if desired, a spreader or conical 45 surface thereon arranged immediately above the fuel outlet.

Other features of the invention will be more clearly understood with reference to the accompanying drawings in which—

50 Figure 1 is a central section of the carbureter, and Fig. 2 shows a modification of a portion of the carbureter.

The carbureter comprises a valve-body A having a conical under surface as illustrated 55 and air passages A¹ A² A³ which conduct

the entering air into the interior of a stem member H and into close proximity with a supply tube or aspirator tube B so that the flow of air past the outlet of the aspirator tube draws fuel from the well of chamber C into which the tube extends, as will be readily understood.

The stem member H has a screw-connection with a surrounding sleeve D connected with the valve-head and sliding in a sleeve E. A duct E¹ permits liquid fuel to flow from the reservoir J through an annular orifice E² formed between a plug E³ and a hollow stem H¹. The orifice E¹ also admits the fuel to the interior of the hollow member D which, co-acting with a conical plug K, admits more or less fuel into the chamber C according to the relative positions of and caused by movement between the conical plug K and the stem H¹. The inflow of fuel to the chamber C is controlled by means of a seat B and a valve M which regulates the flow of fuel from a supply pipe J¹ in the known manner. The cylindrical stem D in conjunction with the outer casing E exerts a dash-pot action upon the movement of the member A.

The upper portion of the outer casing provides a seating at L for the conical surface of the air valve, and air entering 55 through the conduit M is admitted between the seating L and the member A when the latter is lifted from its seating.

It has been found in practice that at high engine speeds the throttle F, acting as an atomizer, does not cause a sufficiently intimate mixture of the fuel and the air issuing from the tube B and the valve-stem H respectively.

The chief feature of the present invention 60 consists in providing an atomizer or baffle plate G immediately above the outlet from the aspirator tube B.

The top or end of the valve-body A is dished or hollowed out and provided with 65 a screw-thread at A⁴ and a projecting ring G¹ from the plate G provided with a similar screw-thread engages in the top of the valve. Ports G² are arranged in the projecting ring G¹ so as to allow the mixture to pass 70 between the plate G and the top of the valve A as shown by the arrows.

It is preferred to arrange on the under- 75 side of the plate G a conical or other spreading surface G³ immediately above the aspirator tube B.

rator tube B so as to deflect the fuel to cause it to intimately mix with the inflowing air.

Fig. 2 shows a modified arrangement of the atomizing plate and part of the air valve structure wherein the plate or disk G is secured to the member A by means of screws G⁴ arranged at intervals around its periphery passing through it and screwing into the head of the valve. The distance between the head of the valve-member A and the plate G may be adjusted by distance pieces or the like G⁵ disposed between the head and the plate G.

Other modifications in detail may be made provided that the spirit of the invention is not departed from.

What I claim as my invention and desire to secure by Letters Patent is:—

1. In a carbureter the combination of, an air valve, a mixing or combining chamber therein for fuel and air, conduits between said chamber and supplies of fuel and air respectively, an outlet from said chamber, a flattened or extended end portion on the valve into which said outlet opens, a disk arranged substantially parallel to and close to the flattened or extended portion of the valve and means to adjust the disk relatively to the flattened or extended portion of the valve.

2. In a carbureter the combination of, an air valve, a mixing or combining chamber therein for fuel and air, conduits between said chamber and supplies of fuel and air respectively, an outlet from said chamber, a flattened or extended end portion on the valve into which said outlet opens, a disk arranged substantially parallel to and close to the flattened or extended portion of the valve, and a spreading means arranged on the disk on that side adjacent the outlet.

3. In a carbureter the combination of, an air valve, a mixing or combining chamber therein for fuel and air, conduits between said chamber and supplies of fuel and air respectively, an outlet from said chamber, a flattened or extended end portion on the valve into which said outlet opens, a disk arranged substantially parallel to and close to the flattened or extended portion of the valve, and a spreading means arranged on the disk on that side adjacent the outlet.

valve, means to adjust the disk relatively to the flattened or extended portion of the valve, and a spreading means arranged on the disk on that side adjacent the outlet.

4. In a carbureter the combination of, an air valve, a mixing or combining chamber therein for fuel and air, conduits between said chamber and supplies of fuel and air respectively, an outlet from said chamber, a flattened or extended portion on the valve and to which said outlet opens, a disk adjustably mounted substantially parallel to the flattened portion of the valve and providing a narrow peripheral slit at the edge of the flattened portion.

5. In a carbureter the combination of, an air valve having a flattened or extended head in connection with a hollow cylindrical portion, a disk adjacent the flattened end, spacing members between the disk and said valve-head with means to secure said disk to the flattened or extended head, a fuel conduit disposed in the cylindrical portion of the valve, means to introduce air to the cylindrical portion and fuel to the fuel conduit respectively and to permit axial movement of the two parts together and a spreader on the disk close to and above the fuel conduit.

6. In a carbureter the combination of, an air valve comprising a hollow stem and a flattened or extended head the underside thereof being conical and tapering toward the stem, a fuel conduit arranged in the hollow stem, means to admit air to the hollow stem and fuel to the fuel conduit respectively, a disk adjustably secured to the flattened head and arranged above the fuel outlet, a casing surrounding the air valve providing a valve-seating for the conical portion of the valve, said casing being opened to the atmosphere by movement of the valve.

In testimony whereof I have signed my name to this specification in the presence of two subscribing witnesses.

GEORGE WILLIAM ALSTON BROWN.
